UNITED STATES PATENT OFFICE.

WILLIAM H. MOHR, OF READING, PENNSYLVANIA.

DESIGN FOR A CEMETERY FLOWER-VASE.

50,279.

Specification for Design.

Patented Feb. 6, 1917.

Application filed November 20, 1916. Serial No. 132,479. Term of patent 7 years.

To all whom it may concern:

Be it known that I, WILLIAM H. MOHR, a citizen of the United States of America, residing in the city of Reading, county of Berks, and State of Pennsylvania, have invented a new, original, and ornamental Design for a Cemetery Flower-Vase, of which the following is a specification, reference being had to the accompanying drawing, forming a part thereof.

In the drawing:—

Fig. 2 is a plan view thereof.

I claim:—

The ornamental design for a cemetery flower vase, as shown.

WILLIAM H. MOHR.
